UNITED STATES PATENT OFFICE.

EDWIN T. EARL AND GUY C. EARL, OF OAKLAND, AND JOHN H. MILLER,
OF SAN FRANCISCO, CALIFORNIA; SAID GUY C. EARL AND SAID MILLER
ASSIGNORS TO SAID EDWIN T. EARL.

REFRIGERATOR-CAR.

SPECIFICATION forming part of Letters Patent No. 633,820, dated September 26, 1899.

Application filed May 31, 1898. Serial No. 682,202. (No model.)

To all whom it may concern:

Be it known that we, EDWIN T. EARL and GUY C. EARL, residing at Oakland, in the county of Alameda, and JOHN H. MILLER, residing at San Francisco, in the county of San Francisco, State of California, citizens of the United States, have invented certain new and useful Improvements in Refrigerator-Cars, of which the following is a specification.

10 Our invention relates to refrigerator-cars, and more particularly to the ice-tanks of such cars and to means for diminishing and increasing the capacity of the tanks in order to employ a smaller or larger quantity of ice. 15 In Letters Patent granted to Edwin T. Earl June 1, 1897, and numbered 583,794, was described an ice-tank for such a car provided with an intermediate floor or false bottom adapted to lie across the tank as a floor or to 20 be turned against the wall of the tank in order to open the latter to its full capacity.

The conditions under which refrigerator-cars are used, particularly in transporting perishable substances over long routes and through varying climates and temperatures, 25 make it desirable to use less ice at some parts of the route and at certain seasons than at others. Thus in starting a car loaded with fruit from a warm climate where ice is expensive it is sometimes desirable to use a small quantity of ice in the upper part of the tank, provided that a comparatively short run will bring the car to a point where ice is cheap and the tanks can be filled. These 30 conditions are found in transporting fruit from the Pacific coast to Eastern points, the run from the coast to the high Sierras, for instance, being made with a small quantity of ice upon the intermediate floor or false 35 bottom and the tanks being filled to their full capacity at mountain-stations, where ice is comparatively inexpensive. It is sometimes desirable also to run the car under ventilation by opening the ice-holes at both 40 ends of the car and using a small quantity of ice in the upper part of the tank at the head end, the air blowing through that ice and then through the car and escaping at the rear end through the open ice-hole there.

45 The object of the present invention is, first,

to provide means for removing the false bottom entirely from the main ice-tank instead of leaving it within such tank after changing its position, and, further, to take advantage of certain features in the construction of the 55 ice-tanks to provide receptacles for the false bottoms communicating with the tanks to receive these bottoms when removed from the tanks.

One form of our invention is particularly 60 adapted to refrigerator-cars provided with end tanks, the upper part of which are extended toward the middle of the car, forming what is known as the "overhead" part 65 of the tank, beneath which is storage-space 70 for the cargo, which is loaded up against the main wall of the tank. The supplementary floor or false bottom can be placed about on a level with the bottom of the overhead tank, and the overhead tank can be made 75 somewhat deeper than usual. It can thus be used as a receptacle for the sliding false bottom when it is desired to open the tank to full capacity. At other times the false bottom will receive and hold the relatively small 80 quantity of ice required.

Another form of our invention provides for a pocket or receptacle for the false bottom in a wall of the ice-tank, in which it can be placed and from which it can be withdrawn. 85

We have illustrated our invention in the accompanying drawings, in which—

Figure 1 is a longitudinal section of one end of a car, showing one ice-tank, the false bottom in the tank, and a receptacle provided 85 for it when withdrawn. Fig. 2 is a horizontal section showing the false bottom made in two parts independently movable by a sliding motion, one of such parts being withdrawn and the other lying as a floor across the tank. 90 Fig. 3 is a cross-section through the ice-tank, looking toward the middle of the car. Fig. 4 is a vertical section showing a pocket arranged in a wall of the tank. Fig. 5 is a horizontal section of the same. Fig. 6 is a detail 95 section of the flexible false bottom shown in Fig. 5. Fig. 7 shows a different arrangement of mechanical means for moving the false bottom.

A represents a refrigerator-car; B, an ice-

tank at one end; C, an ice-hole in the roof provided with a hatch or cover D, and E the ordinary bottom of the tank, through which the cold air escapes to enter the interior or storage-space of the car.

F is an extension or overhead tank projecting from the main tank under the car-roof and having a grating or screen front f. This overhead tank is in Fig. 1 shown as somewhat deeper than ordinarily made. Beneath the overhead tank is cargo-space for loading boxes, crates, &c., up against the front partition or wall of the main tank, and an opening F' is provided in the main tank just beneath the overhead extension, which is a direct escape for warm air into the ice-tank from the cargo-space beneath the overhead tank.

G is a supplementary floor or false bottom, which may be formed in one, two, or more sections. It is constructed as a grating to pass the cooled air and water through and downward. We have shown it as composed of two sections, which are convenient to handle and can be shifted without levers or other mechanical means, although such means can be employed and have been illustrated in the drawings. When in position as a floor across the tank the bottom or its plurality of sections is supported by cleats 11, secured to the front and rear walls of the tank, and we prefer to provide cleats 22 along the side walls of the tank to guide the bottom in its bodily movement.

In Figs. 1 and 3 the extension or overhead tank is increased somewhat beyond its usual depth, so that its bottom 4 lies just below the false bottom. When so constructed, the false bottom can be pushed bodily and by a sliding movement into the overhead tank, which forms a receptacle for it. When the bottom is formed in a plurality of sections, the sections can be separately pushed into the overhead tank and pulled therefrom. When the bottom is shifted by hand, the ice can all be transferred to one section, then the cleared section pushed into the extension-tank, then all the ice discharged into the main tank, and the remainder of the false bottom pushed into the extension, and this course can be followed, if desired, when means are provided for mechanically shifting the false bottom. We have illustrated in Fig. 1 certain means for this character—viz., a chain H, secured to the false bottom or each of its sections and extending into the extension-tank around guide-pulleys 3 and 3. The chain then passes to a point near one of the ice-holes, where its end may be caught and held in any suitable way. By means of this chain the false bottom can be pulled into the extension-tank before or after the ice has been shifted from it, the ice in the former case falling into the main tank below.

We prefer to provide the overhead extension-tank with special means to receive the false bottom in order that there may be no interference with its movements by ice in that

tank. For this purpose we have provided a pocket. (Shown in Fig. 1.) The pocket K in Fig. 1 is formed by a partition I, which may be a grating in the overhead tank in connection with the bottom of the tank, the mouth of the pocket being about opposite the edge of the false bottom G.

In Figs. 4 and 5 we have illustrated a modification of our invention, which, however, contains the essential feature of a pocket communicating with the ice-tank and adapted to receive the false bottom. The pocket in this case is formed in a wall of the ice-tank, and we have shown such a pocket L formed in the front wall of the tank and having an opening 5 communicating with the tank. The false bottom is preferably made in two or more sections, as before described, and in order to render it easier to stow and withdraw the bottom we prefer to make it or each of its sections flexible and in as many parts jointed together as may be necessary. We have shown each section as composed of two parts M and M jointed together on a rod 6, so that the joints can break upwardly and allow the bottom to enter the hole in the wall of the tank and be turned downwardly into the pocket.

In case it should not be desired to have the extension or overhead tank as deep as shown in Fig. 1, but to provide it with a pocket for the false bottom, which would be above the level of such false bottom, it may be found convenient to use a flexible false bottom in connection with the pocket in the overhead tank. The use of such a flexible false bottom is therefore not necessarily confined to a construction in which the pocket is placed in the wall of the ice-tank.

In Fig. 7 we have shown another form of device for moving the false bottom, which is designed to act automatically. In this case a chain H' is secured to the front edge of the false bottom or its sections, to the free end of which is secured a weight O. This chain is guided by a pulley 7 into the pocket or a guide in the wall of the tank, and the false bottom is held in position by some form of catch, such as that shown at 8. The releasing of the catch permits the weight to fall, drawing the false bottom horizontally into the extension-tank.

Whether the pocket be formed in connection with the overhead tank or in a wall of the main tank, the false bottom can be entirely removed from the main tank and safely stowed where it is conveniently accessible.

We do not limit ourselves to the exact constructions described and shown, as within the limits of the following claims modifications may be made without departing from the spirit of our invention.

Having thus described our invention, what we claim as new, and desire to secure by Letters Patent, is—

1. In a refrigerator-car, the combination with the ice-tank having an ice-hole, of a slid-

ing false bottom for diminishing the capacity of the tank, a receptacle for receiving and stowing said false bottom to restore the capacity of the tank, and a connection accessible through the ice-hole for mechanically moving said false bottom.

2. In a refrigerator-car, the combination with the ice-tank having an ice-hole, of a sliding false bottom for diminishing the capacity of the tank, a receptacle for receiving and stowing said false bottom to restore the capacity of the tank, a connection for mechanically moving said false bottom; said connection being secured at one end of the false bottom, and having a free end accessible through the ice-hole for applying power thereto.

In testimony whereof I, the said E. T. EARL, have affixed my signature, in presence of two witnesses, this 30th day of April, 1898.

EDWIN T. EARL.

Witnesses:

T. M. SIMPSON,
W. F. CRONENNILLER.

In testimony whereof we, the said GUY C. EARL and JOHN H. MILLER, have affixed our signatures, in presence of two witnesses, this 5th day of May, 1898.
